COMBINED TELEPHONE BASE AND MOUTH- PIECE STERILIZING DEVICE

George R. Cobb, White Rock, British Columbia, Canada

Application June 12, 1959, Serial No. 56,324

Term of patent 7 years

(Cl. D26—14)

Figure 1 is a perspective view of a combined telephone base and mouthpiece sterilizing device, showing my new design;

Figure 2 is a side elevational view thereof, the opposite side being substantially conventional;

Figure 3 is a rear elevational view; and

Figure 4 is a top plan view of the housing for the sterilizing lamp detached from the base of the telephone.

I claim:

The ornamental design for a combined telephone base and mouthpiece sterilizing device, as shown and described.
